UNITED STATES PATENT OFFICE.

JOHN O. JOHNSON, BURT W. REDICK, AND HARRY M. HENDERSON, OF PORTLAND,
OREGON.

SAFETY SWITCH-LOCK AND INDICATOR.

1,180,723.

Specification of Letters Patent. Patented Apr. 25, 1916.

Application filed July 8, 1915. Serial No. 38,802.

To all whom it may concern:

Be it known that we, JOHN O. JOHNSON, BURT W. REDICK, and HARRY M. HENDERSON, citizens of the United States, residing at Portland, in the county of Multnomah and State of Oregon, have invented certain new and useful Improvements in Safety Switch-Locks and Indicators; and we do declare the following to be a full, clear, and exact description of the invention, such as will enable others skilled in the art to which it appertains to make and use the same.

This invention relates to improvements in safety switch locks and indicators for use on a switch stand on a railroad equipped with a block signaling system.

The main object of the invention is to provide a device so constructed as to maintain the signals in their danger position until the switch is wholly closed and its operating handle or lever securely locked.

Another object is to provide a simply constructed and efficient device of this character which may be readily applied to any switch stand commonly in use by all railroads.

It is a common occurrence for switchmen to leave switch locks unlocked and this permits any passer-by to wholly or partially open the switch. When the switch is opened even for a fraction of an inch, the usual signal gives no indication of this fact, and the passage of a train over such a switch frequently results in an accident. It is to overcome this defect and to protect the railroad company against carelessness of its employees that this invention is designed.

With these and other objects in view, the invention consists of certain novel features of construction, and the combination and arrangement of parts as will be more fully described and claimed.

In the accompanying drawings: Figure 1 represents a diagrammatic view showing this invention applied with the signal indicating a clear track; Fig. 2 is a similar view with the signal showing a blocked track; Fig. 3 is a front elevation of a switch stand equipped with this improvement; Fig. 4 is a side elevation thereof; Fig. 5 is a horizontal section taken substantially on the line 5—5 of Fig. 3; Fig. 6 is a similar view taken on the line 6—6 of Fig. 3 showing the attachment in operative position for locking the switch; Fig. 7 is a similar view showing the attachment with the parts in the position assumed

when the switch is unlocked; Fig. 8 is a transverse vertical section taken substantially on the line 8—8 of Fig. 6 with the parts in operative position; Fig. 9 is a similar view showing the key in the act of releasing the locking pin; Fig. 10 is a horizontal section taken on the line 10—10 of Fig. 11 with the locking pin shown in operative position; Fig. 11 is a transverse vertical section taken on the line 11—11 of Fig. 7; Fig. 12 is a vertical longitudinal section taken on the line 12—12 of Fig. 7; Fig. 13 is a vertical section taken on the line 13—13 of Fig. 6; Fig. 14 is a side elevation partly in section of the locking key.

In the embodiment illustrated, this improvement is shown applied to a switch stand S of ordinary construction mounted on a suitable base B and having a signal shaft s operatively mounted therein which extends through a slotted table T fixed on the stand S and which carries on its lower end a crank C for connection with a switch in the usual manner, through the medium of the connecting rod R. A yoke Y is secured to the spindle or shaft s above the table T and has an actuating lever L pivotally mounted thereon and which pivotally connects said lever with the table. This operating lever L is adapted to be lowered on its pivotal support at the ends of its throw into one or the other of the slots S' in the table adjacent to which are the usual stop lugs l for limiting the throw of the lever, and in either of its lowered positions, the lever may be secured by a pin 1 constituting a part of this improved attachment which is mounted on a chain 2 here shown connected with the lever by means of an apertured lug L' and which is designed to be secured by means hereinafter described. The opposed walls of the slots or recesses S' in the table have depending extensions 3 which are provided with horizontally alined apertures 4 positioned to aline with an aperture 5 which extends transversely through the lever L, so that on the insertion of the pin 1 in the apertures 4 of the table extensions 3, said pin will pass through the aperture in the lever and thus prevent the lever from being operated until the pin is withdrawn, said pin being locked in operative position by the means now to be described and which constitute a part of this attachment.

Secured to the table T between the slots

or recesses S' is a housing 6 here shown substantially triangular in form with the outer upright wall 7 thereof curved longitudinally and secured at its upper edge to the edge 5 of the table by securing screws or other suitable fastening elements, as is shown clearly in Figs. 3 and 5, the casing or housing proper extending under the table between the lever receiving sockets or recesses 10 S' , the side walls of said casing being provided with apertures 8 which register with the apertures 4 in the side walls of the slots or sockets S' to provide for the passage into the housing of the locking point 1^a of the 15 pin 1. This pin point 1^a is shown provided at its base with an annular shoulder 1^b which is designed to be engaged when in operative position by a locking element arranged within the casing 6 for retaining the 20 pin in operative position and preventing its unauthorized withdrawal, as will be hereinafter more fully described.

A supporting block 9 is shown mounted in the casing 6 and composed of a plurality of 25 sections 12 and 18 of insulating material superposed on each other and secured to the base plate 10 of the casing by means of suitable bolts 11. As shown the lower section 12 of this block is made larger than the upper section 18 and both of them are substantially triangular in form with their vertices arranged toward the vertex of the casing as is shown clearly in Figs. 6, 7 and 10. Binding posts 13 and 14 extend through 30 these insulating plates and have connected therewith the wires 15 and 16 of an electric circuit, which are connected with a semaphore or other signal 17 disposed at a suitable point on the track to which the device 35 is applied, as is shown clearly in Figs. 1 and 2.

The upper or top section 18 of the block 9 is provided with obliquely disposed slots or sockets 19 which extend through the 40 side walls of said section and converge and meet at the front edge or wall thereof and which are designed to receive a contact plate 20 which is here shown connected with the wire 16 of the binding post 14, and which 45 is provided with a contact point 21 which projects beyond the front edge of the section 18 as is shown clearly in Fig. 10, said contact point being composed of any suitable material preferably platinum, which 50 is the material used ordinarily for this purpose. A spring contact plate 22 is connected with the other binding post 13 and is here shown in the form of a metal strip, preferably composed of copper, said strip 55 being arranged on one side edge of said section and provided with inwardly projecting laterally extending apertured ears 23 through which the binding post 13 extends and connects said strip with the wire 15 60 of the electric circuit. This strip 22 ex-

tends around the front edge of the section 18 and has a deflected terminal 24 arranged in the path of the point of the pin 1 so that when said pin is inserted through the apertures 4 and 5 of the table and lever, the 70 point thereof will engage said deflected terminal 24 and force the spring metal strip outward away from the section 18 which it is normally designed to hug. This contact plate 22 is provided with a contact point 25 75 on its inner face arranged in position to engage the contact point 21 of the co-operating plate 20 when said strip is in released position and by means of which the circuit is closed, and on the closing of this circuit, 80 the semaphore 17 is actuated to position the signal 17' thereof to indicate danger, and when the plate or strip 22 is moved outward to disengage its contact from the contact 21 of the plate 20, the circuit is broken and 85 the semaphore signal will indicate safety or a clear main track.

A pin locking member is here shown in the form of a cross bar 26 secured midway its ends to a spring arm 27 which is secured 90 at one end to the vertex of the upper face of the block section 18 as is shown clearly in Figs. 6 and 7 and which projects forwardly beyond the cross bar 26 and is provided at its free end with a T-shaped head 95 28 having a cam 29 on its lower face for a purpose to be described. The cross bar 26 is provided at its free ends with diverging obliquely disposed arms 30 provided on their lower faces with depending lips 31 100 which are designed to perform the function of catches for engaging the annular shoulder 1^b of the pin 1 when in operative position for locking said pin against withdrawal, as is clearly shown in Figs. 6 and 105 13. This latch or locking lip 31 which is carried by each of the arms 30 is so positioned as to engage the shoulder 1^b when the pin has been inserted sufficiently to bring the point 1^a into engagement with the deflected end 24 of the contact plate 22 and force it away from the block section 18 a sufficient distance for disengaging its contact point 25 from the contact point 21 of the other contact plate 20 as is clearly shown 110 in Figs. 6 and 10, so that when said pin is in this position, it will be locked to hold said contact plates away from each other and thereby break the circuit, so that the indicator connected therewith will exhibit 115 a safety signal, showing that the main track is clear and that the switch is locked, as this pin when so positioned is inserted through the lever L and can only pass therethrough when said lever is in lowered position after it has been actuated to lock the switch. The cross bar 26 is provided with 120 two arms 30 and the table T with two sockets S' so that the device may be applied to a stand positioned either at the right side or 125 130

the left side of the track, and when the position of the stand is reversed, it will of course be understood that it will be necessary to reverse the positions of the contact plates 20 and 22, and for this reason, the upper section 18 of the block 9 is provided with the diverging slots 19 so that the plate 20 may be positioned equally well in either of said slots and the plate 22 secured to either side of the block section according to the position in which the switch stand is located.

The T-shaped head 28 of the spring arm 27 which carries the pin locking latches, has the cam 29 thereof positioned over a key-hole slot 32 formed in the curved front wall of the easing 6 and in which a key 33 is designed to be inserted for releasing the pin by raising the arm 27 through the T-shaped head 28 and consequently raising the cross bar 26 carried by said arm and thereby lifting the latches or locking lips 31 a sufficient distance to disengage them from the annular shoulder 1^b of the pin 1 and thus permit said pin to be withdrawn to release the lever L. This raising of the bar 27 is accomplished by means of a ward 34 carried by the key 33 which on the turning of said key engages the cam 29 and raises the bar or arm 27 as is shown clearly in Fig. 9.

From the above description, it will be obvious that when the switch has been actuated by the lever L and said lever swung downwardly into engagement with one or the other of the slots S' according to the position in which the stand is located and the pin 1 is inserted through the registering apertures in the side walls of said slot and in said lever, that the semaphore signal will indicate danger until said pin is inserted far enough to cause the point 1^a to engage the deflected terminal 24 of the contact plate 22 and to force said plate outwardly a sufficient distance to break the contact between it and the plate 20, and that when said pin has been inserted in this position it becomes automatically locked by the lip 31 on the spring arm 30 which springs into engagement with the shoulder 1^b of said pin and which reliably holds said pin and prevents all possibility of its being disengaged and the lever released by an unauthorized person, it being necessary that the key 33 be employed in the manner above described before said pin can be released. After said pin is inserted as thus described, the contact between the plates being broken, the semaphore signal will be set to indicate safety or a clear track, and the engineer of a passing train will know that the switch is properly set and locked when said signal is in this position, and when the signal is set at danger he will know that the switch is either open or not locked, and thereby liable to be opened at least partially.

It will be understood that in order to throw the switch it is necessary to release the lock pin which is accomplished by inserting the key 33. This key raises the latch spring 27 and the pressure of the contact plate 22 on the point of pin 1 forces it sufficiently outward to disengage it from the latch 31 and out of the path of said plate and thereby permits the contacts to meet and complete the circuit and thus set the signal to indicate danger.

Two lugs 35 extend laterally inward from the inner face of the outer wall 7 of the housing 6 at points spaced slightly above the ends of the arms 30 of the pin locking member and which are designed to prevent said arms from being forced upwardly to such an extent as to strain the spring 27 with which they are connected and thereby insure the reliable locking of the pin.

A pivoted guard 32' is mounted on the outer face of the housing wall 7 in position to swing normally over the key hole 32 and protect it against the elements.

We claim as our invention:

1. The combination with a switch stand having a slotted table and a switch lever pivoted to enter the slot in said table, the walls of said slot and said lever having apertures to register when the lever is in position in said slot, a lock casing having an aperture in one wall registering with the apertures in said slot walls, a pin for insertion through said registering apertures, and coöperating elements carried by said pin and casing for locking the pin against withdrawal after it has been inserted a predetermined distance in said casing.

2. The combination with a switch stand having a slotted table and a switch lever pivoted to enter the slot in said table, the wall of said slot and said lever having apertures positioned to register when the lever is in position in said slot, a lock casing having an aperture in one wall registering with the apertures in said slot walls, a pin for insertion through said registering apertures, and means for locking said pin against withdrawal after it has been inserted a predetermined distance in said casing.

3. The combination with a switch stand having a slotted table and a switch lever pivoted to enter the slot in said table, the walls of said slot and said lever having apertures positioned to register when the lever is in position in said slot, a lock casing having an aperture in one wall registering with the apertures in said slot walls, a pin for insertion through said registering apertures, means for locking said pin against withdrawal after it has been inserted a predetermined distance in said casing, and signal controlling means arranged in the path of said pin and operable on the insertion of said pin in locked position to set the signal.

- at safety and to reverse it on the withdrawal of said pin from said position.
4. The combination with a signal and switch stand and a switch lever, means for holding the switch lever in locked position, means for locking said holding means in operative position, contacts connected with said signal and normally in engagement with each other, one of said contacts having a spring arm arranged in the path of said lever holding means and adapted to be engaged by said means when said means is positioned for engagement by said locking means, whereby said contacts are separated.
5. The combination with a signal, a switch stand and a switch lever, of means for holding the switch lever in locked position, means for locking said holding means in operative position, fixed and movable contact plates connected with said signal, said movable contact plate having a deflected terminal positioned in the path of said lever holding means and adapted to be engaged thereby when said holding means is positioned for locking engagement by said locking means, whereby said contact plates are separated and the signal thereby set to indicate the locking of said holding means.
6. The combination with a switch stand and a switch lever, of a lock casing, a support of insulating material mounted in said casing and having a V-shaped seat therein with its apex opening through one side wall of said support, a contact plate housed in said seat and having a contact point extending through the apex thereof, a co-operating spring contact plate secured at one end to said support and having a contact point arranged to register with the contact point of the other plate, said spring plate having its terminal deflected, means insertible in said casing for holding the switch lever in locked position, and adapted to engage the deflected end of said contact plate on its insertion in said casing, a predetermined distance and thereby separate said contacts, and a signal controlled by the position of said contacts in relation to each other.
7. The combination with a signal, a switch stand and a switch lever, of a lock casing, alined apertured lugs on said switch stand between which said lever is adapted to swing, said lever having an aperture therein registering with the apertures in said lugs, said casing having an aperture in one wall registering with the apertures in said lugs and lever, a pin insertible through said alined apertures in said lugs, lever and casing and having a shouldered point adapted to be projected into said casing, a latch for engaging the shoulder of said pin for locking the pin in operative position, means connected with said signal and arranged in the path of said pin whereby on the insertion of said pin to locked position said means are actuated to operate said signal.
8. The combination with a signal, a switch stand and a switch lever, of a lock casing, alined apertured lugs on said switch stand between which said lever is adapted to swing, said lever having an aperture therein registering with the apertures in said lugs, said casing having an aperture in one wall registering with the apertures in said lugs and lever, a pin insertible through said alined apertures in said lugs, lever and casing and having a shouldered point adapted to be projected into said casing, a resilient member having a depending lip for engaging the shoulder of said pin for locking the pin in operative position, and key actuated means for releasing said pin.
9. The combination with a signal, a switch stand and a switch lever, of a lock casing, alined apertured lugs on said switch stand between which said lever is adapted to swing, said lever having an aperture therein registering with the apertures in said lugs, said casing having an aperture in one wall registering with the apertures in said lugs and lever, a pin insertible through said alined apertures in said lugs, lever and casing and having a shouldered point adapted to be projected into said casing, a resilient member having a depending lip for engaging the shoulder of said pin for locking the pin in operative position, and a key actuated cam carried by said member for releasing said pin.
10. The combination with a signal, a switch stand and a switch lever, of a lock casing, alined apertured lugs on said switch stand between which said lever is adapted to swing, said lever having an aperture therein registering with the apertures in said lugs, said casing having an aperture in one wall registering with the apertures in said lugs and lever, a pin insertible through said alined apertures in said lugs, lever and casing and having a shouldered point adapted to be projected into said casing, a resilient member having a depending lip for engaging the shoulder of said pin for locking the pin in operative position, and means for raising said member to release said pin.
11. The combination with a signal, a switch stand and a switch lever, of a lock casing, alined apertured lugs on said switch stand between which said lever is adapted to swing, said lever having an aperture therein registering with the apertures in said lugs, said casing having an aperture in one wall registering with the apertures in said lugs and lever, a pin insertible through said alined apertures in said lugs, lever and casing and having a shouldered point adapted to be projected into said casing, a resilient member having a depending lip for engag-

ing the shoulder of said pin for locking the pin in operative position, and key controlled means for raising said member to release said pin.

- 5 12. The combination with a signal, a switch stand and a switch lever, a table on said stand having laterally spaced slots therein, a lock casing carried by said table between said slots, the walls of said slots 10 and said casing, and said lever having registering apertures therein, a support of insulating material in said casing, contact plates reversibly mounted on said support, and connected with said signal, lever holding means 15 insertible in the apertures of said slot walls, lever and casing, means mounted on said support for locking said holding means, one of said contact plates having means positioned in the path of said holding means and 20 operable thereby to separate the plates on the locking of said holding means.

13. The combination with a signal, a switch stand and a switch lever, of means for holding the switch lever in locked position, means for locking said holding means in operative position, circuit breaking means arranged in the path of said lever holding means and operable on the engagement of said holding means by said locking means to 30 break the circuit, said circuit breaking means being connected with said signal, and means for moving said locking means to releasing position, said circuit breaking means including a spring arm for forcing said holding 35 means out of the path of said locking means and out of the path of said circuit breaking means on the operation of said lock releasing means.

14. The combination with a signal, a switch stand and a switch lever, of means for holding the switch lever in locked position, means for locking said holding means in operative position, circuit breaking means arranged in the path of said lever holding 45 means and operable on the engagement of said holding means by said locking means to break the circuit, said circuit breaking means being connected with said signal, key actuated means for moving said locking means to 50 releasing position, and means for automatically forcing said lever holding means outward on the movement of said locking means to releasing position.

15. The combination with a signal, a switch stand and a switch lever, of means for holding the switch lever in locked position, means for locking said holding means in operative position, key actuated means for moving said locking means to releasing 55 position to disengage said holding means, fixed and movable contacts, said movable contact being spring pressed toward said fixed contact and having a member arranged in the path of said lever holding means, whereby the contacts are separated 60

on the insertion of the holding means into locking position and engage each other on the release of said holding means, said spring pressed contact member operating to force said holding means out of locking 70 position on the release of said holding means.

16. In combination, a track switch, a signal to indicate the condition of the switch, electric means for operating the signal including a circuit connector, a lever for operating the switch, and a locking member movable across the path of movement of the switch lever to lock it in safety position, said circuit connector being arranged in 75 the path of movement of the locking member to be actuated by it after such member has locked the lever, said locking member maintaining the circuit connector in its actuated position until such member starts 80 to move out of operative locking connection with the switch lever.

17. In combination, a main track switch, a signal to indicate the condition of the switch, electric means for operating the signal including a normally open circuit connector, a lever for operating the switch, and a slidably mounted pin normally arranged across the path of movement of the switch lever to lock it in safety position, said circuit connector being arranged in the path of movement of the pin to be actuated by one 90 end of it to its normal open position in which it is retained until the pin is moved in a direction to retract it from its locking 95 engagement with the switch lever.

18. In combination, a track switch, a signal to indicate the condition of the switch, electric means for operating the signal including a circuit connector, a lever for operating the switch, a locking member movable across the path of movement of the switch lever to lock it in safety position, said circuit connector being arranged in the path of movement of the locking 105 member to be directly actuated by it after it has locked the lever and to be maintained in such actuated position until released by the retraction of the locking member, an increased latch for locking the said member 110 in operative position, and key actuated means for moving said latch to releasing position.

19. In combination, a track switch, a signal to indicate the condition of the switch, 120 electric means for operating the signal, including a circuit connector, a lever for operating the switch, a stand for the lever having a seat to receive it when the lever is in safety position, a shouldered locking pin 125 slidably across the seat and lever to lock the latter, a lock casing into which said shouldered pin is projected when in operative position, said circuit connector being arranged in the casing and in the path of movement 130

of said pin, a latch in the casing to engage the shouldered portion of the pin to lock it, and key actuated means for moving said latch to releasing position.

5 20. In combination, a track switch, a signal to indicate the condition of the switch, electric means for operating the switch including a circuit connector, a lever for operating the switch, a stand for the lever having a seat to receive it when the lever is in safety position, a shouldered locking pin slideable across the seat and lever to lock the latter, a lock casing into which said shouldered pin is projected when in 10 operative position, said circuit connector being arranged in the casing and in the path of movement of said pin, a spring latch in the casing to engage the shoulder on the pin to lock it, and a cam operatively connected with the latch and adapted to be engaged and actuated by a key inserted in the casing whereby the pin may be released.

15 21. In combination, a track switch, a signal to indicate the condition of the switch, electric means for operating the signal including a circuit connector, a lever for operating the switch, a stand for the lever having a seat to receive it when the lever is in safety position, a shouldered locking pin 20 slideable across the seat and lever to lock the latter, a lock casing into which said shouldered pin is projected when in operative position, said circuit connector being arranged in the casing and having a contact carrying spring arranged in the path of movement of the shouldered end of said pin to be actuated by the latter when moved to its operative position to lock the switch lever, a latch in the casing to engage the 25 shoulder of the pin to lock the latter, and key actuated means for moving said latch to releasing position.

30 22. In combination, a track switch, a switch stand having spaced seats, a lever for operating the switch mounted on said stand and adapted to be positioned into either of said seats, a lock casing arranged between said seats, a lever locking pin to be positioned across either seat and across the path of 35 movement of the lever to lock it in either seat, said member when in either operative position having a portion projected into said casing, a double latch in the casing to engage said pin when in either of its two positions, and key actuated means for moving 40 said latch to releasing position.

45 23. In combination, a track switch, a switch stand having spaced seats, a lever for operating the switch mounted on said stand and adapted to be positioned into either of 50 said seats, a lock casing arranged between said seats, a lever locking pin to be positioned across either seat and across the path of 55 movement of the lever to lock it in either seat, said member when in either operative position having a portion projected into said casing, a double latch in the casing to engage said pin when in either of its two positions, and key actuated means for moving 60 said latch to releasing position.

of movement of the lever to lock it in either seat, said member when in either operative 65 position having a portion projected into said casing, a double latch in said casing to engage the pin in either of its two positions to lock the same, key actuated means for moving said latch to releasing position, a signal 70 to indicate the condition of the switch, a circuit connector in the casing having reversibly mounted contact members one of which is normally positioned in the path of movement of said pin when projected across one 75 of said lever seats, and electric means operatively connected to said circuit connector for operating said signal.

24. In combination, a track switch, a switch stand having a lever receiving seat, 80 a lever for operating the switch and movable into said seat, a lock casing, a lever locking pin projectable across the seat and path of movement of the lever to lock it in the seat, said pin when in operative position projecting into said casing, a latch in the casing to engage said end of the pin, and key actuated means for moving said latch to releasing position.

25. In combination, a track switch, a 90 switch stand having a lever receiving seat, a lever for operating the switch and movable into said seat, a lock casing, a lever locking pin projectable across the seat and path of movement of the lever to lock it in 95 the seat, said pin having a shouldered end projecting into the casing when the pin is in operative position, a spring latch in the casing to engage the shoulder of said pin, and a cam operatively connected to the latch 100 to be actuated by a key inserted in the casing to move the latch out of engagement with the pin.

26. In combination, a track switch, a switch stand having a lever receiving seat, 105 a lever for actuating the switch movable into said seat, a locking pin projecting across the seat and the path of movement of the lever to lock it in safety position, a lock casing to receive said pin when in operative 110 position, a latch in the casing to engage and lock the pin, key actuating means for moving said latch to releasing position and a spring in the casing engaged by the pin when in locked position and adapted to project the pin outwardly when released from the latch.

In testimony whereof we have hereunto set our hands in presence of two subscribing witnesses.
